UNITED STATES PATENT OFFICE.

WILLIAM L. SEELIG, OF ST. LOUIS, MISSOURI.

CASH-FARE-RECEIPT FORM.

1,014,334.

Specification of Letters Patent.

Patented Jan. 9, 1912.

Application filed March 29, 1909. Serial No. 486,617.

To all whom it may concern:

Be it known that I, WILLIAM L. SEELIG, a citizen of the United States, residing at the city of St. Louis, in the State of Missouri, have invented a certain new and useful Cash-Fare-Receipt Form, of which the following is such a full, clear, and exact description as will enable any one skilled in the art to which it appertains to make and use the same, reference being had to the accompanying drawings, forming part of this specification.

The object of my invention is to provide a cash fare receipt form which will be more convenient and satisfactory than those heretofore in use and one which will contain a portion adapted to be used as a hat check.

My invention consists of the various novel features which will be described herein and will be pointed out in the claims annexed hereto.

In the accompanying drawings which illustrate my invention, Figure 1 represents a side view of a pad of my novel receipt forms, the sheets being separated at the bottom. Fig. 2 is a face view of the lower sheet of the form. Fig. 3 is a face view of the upper sheet of the form and Fig. 4 shows the reverse side of Fig. 3.

Like marks of reference refer to similar parts in the several views of the drawings.

The sheet shown in Fig. 3 hereinafter called sheet 3 is superimposed on the sheet shown in Fig. 2 hereinafter called sheet 2 in such a manner that corresponding markings on the two sheets coincide. The upper part of the back of sheet 3 is carbonized as shown in Fig. 4, the carbon extending far enough down to cover the blank space at the top of part 7 of sheet 2. The forms are bound together in a pad by means of a staple or in any other suitable manner. As is shown in the drawings, part 5 above the weakened line 6 contains blanks for the insertion of the

station number and the amount paid and also printed matter constituting it a receipt for fare. The part 7 below the weakened line contains blanks for the insertion of the number of the station of destination and also month and day indications arranged in parallel columns by means of which the date of passage may be indicated with a punch, pencil, or in any other desired manner. Since sheet 3 lies above sheet 2 in the position heretofore described and has a part of its back carbonized, it will be apparent that

the necessary indications can be made simultaneously on both sheets. After being suitably marked sheet 3 is detached and retained by the conductor. Sheet 2 is then detached from the pad and divided into sections along the weakened line 6, the lower section being placed wherever convenient so that the station number will be exposed to view and the upper section being given to the passenger as a receipt for fare. The advantages of this form of receipt are that it is of a convenient size and does not require any box or holder. It can be issued rapidly since the necessary hat check can be prepared at the same time as the auditor's advice. Another important advantage is that this receipt cannot be issued incomplete, thereby avoiding all guess work as to the stations between which the passenger has traveled.

Having fully described my invention, what I claim as new and desire to secure by Letters Patent of the United States is:

1. A cash fare receipt form comprising two superimposed sheets and means for transferring markings from the upper sheet to the lower sheet, the upper sheet bearing a printed form of an auditor's advice of cash fare paid, the lower sheet being divided by a transverse weakened line into two sections, one section bearing a printed form of a passenger's receipt for fare paid and the other section having an appropriately located space for indicating the destination and designated as a hat check, the blank spaces on the upper sheet being so positioned with reference to the blank spaces on the lower sheet that when properly filled in the markings will be transferred to the lower sheet to make one section thereof a complete receipt for fare and the hat check section indicate the destination.

2. A cash fare receipt form comprising two superimposed printed sheets, a part of the back of the upper sheet being carbonized and the lower sheet being divided into two parts by a transverse weakened line, each of said sheets having month and day indications and properly designated spaces for the amount of fare and stations, said indications and spaces on each sheet being positioned to register with like indications and spaces on the other and so arranged that the upper part of the lower sheet will contain the spaces for indicating the station of embarkation and the fare paid, and the lower part of

said sheet will be provided with a suitable space for indicating the destination.

3. A cash fare receipt form comprising two superimposed sheets, the upper sheet having near the top thereof suitable spaces and markings for indicating the station of embarkation and the amount of fare paid, near its center a space for indicating the destination station and on its lower part a 10 table of months and days, the lower sheet being provided with like spaces and markings identically arranged, said lower sheet

being divided into two portions by a transverse weakened line immediately above the space for the destination station, and transfer means whereby markings may be simultaneously made on both sheets. 15

In testimony whereof I have hereunto set my hand and affixed my seal in the presence of the two subscribing witnesses.

WILLIAM L. SEELIG. [L.S.]
